Leonhard Schulze of Philadelphia Penn. DES. 2460

Ass'n to

Thomas Mills & Bro. of same place,
Sellers Patent, No. 2460, dated Sept 25. 1866.

Design for a Candy Figure.

The Schedule referred to in the Seller's Patent and making part of the same.

To all whom it may concern:

Be it known that I, Leonhard Schulze of the City of Philadelphia and State of Pennsylvania, have originated and designed a new figure for castings in Candy, of which the following is a full and exact description, reference being had to the accompanying photograph making part of this Specification.

The Design relates to that class of Figures which are cast hollow of transparent, or opaque candy, and are extensively used as toys for ornamenting Christmas Trees etc. They are made by pouring the heated liquid candy into a metallic mould, after that portion of the candy, which comes in contact with the mould has crystallized and hardened to form a shell of sufficient strength, the inner, yet liquid portion is forced out again and the hollow casting is then removed from the mould which to this end is arranged to separate in two or more parts.

The Figure represents the goddess of Liberty; the posture and details of configuration being fully shown in the accompanying photographs.

What I claim as my invention and desire to secure by Seller's Patent is
The Design for a Candy Figure herein set forth.

Witnessed

Theodore Bergner.
Chas. E. Puncwalt.
